Primary Examiner — Paula Allen Greene(74) *Attorney, Agent, or Firm* — HSML P.C.(57) **CLAIM**

The ornamental design for an earphones, as shown and described.

DESCRIPTION

FIG. 1 is a Top Front Perspective view thereof.

FIG. 2 is a Front view thereof.

FIG. 3 is a Rear view thereof.

FIG. 4 is a Left view thereof.

FIG. 5 is a Right view thereof with a broken line box **8** indicating the portion of FIG. 5 which is shown in FIG. 8.

FIG. 6 is a Top view thereof.

FIG. 7 is a Bottom view thereof; and,

FIG. 8 is an enlarged partial view of FIG. 5 thereof.

The features shown in broken lines depict portions of the earphones that form no part of the claimed design.

The dot-dash broken lines surrounding the earphones in FIG. 5 and illustrated in the enlarged view of FIG. 8 form no part of the claimed design.
